UNITED STATES PATENT OFFICE.

JOHN ELLIOT PEIRCE, OF DAYTON, OHIO.

DESIGN FOR A CABINET.

SPECIFICATION forming part of Design No. 23,974, dated January 29, 1895.

Application filed December 24, 1894. Serial No. 532,884. Term of patent 3½ years.

To all whom it may concern:

Be it known that I, JOHN ELLIOT PEIRCE, a citizen of the United States, residing at Dayton, in the county of Montgomery and State 5 of Ohio, have invented and produced a new and original Design for a Cabinet; and I do declare the following to be a full, clear, and exact description of the same, reference being had to the accompanying drawing, forming a part thereof.

This design relates to cabinets in which goods of various kinds may be displayed or stored, and has for its object to provide a cabinet having its own novel, ornamental, and 15 characteristic features.

The main or leading features of the design consist of a casing or body, of upright-rectangular form, in front and side elevation; and of cubic form in top and bottom plan 20 views. The cabinet has four equal sides, and upon the left-hand portion of each side, there is a vertical row of oblong-rectangular panels.

The design is illustrated in the accompanying pictorial reproductions, in which is shown 25 a perspective view of a cabinet embodying the design.

Referring in detail to said drawing,—the cabinet has four sides, each of which is a facsimile of the one prominently shown in the 30 view, and consists of the following ornamentalations:

(A) designates a sunken, upright-rectangular panel, which is inclosed on either side by upright strips (B) and (C).

(D) designates a vertical row of sunken, oblong-rectangular panels on the left of, and parallel with the strip (C), and occupying a left-hand portion of each side of the cabinet. These sunken panels (D), are each inclosed by a correspondingly shaped frame. These 35 frames are separated by horizontal strips (a) that join with the upright strip (C), and the vertical end strip (F), the latter strip extending around the corner, and forming the upright strip (B) on the next adjacent side of 40 the cabinet.

(G) designates a square base, curving inwardly as at (g), and upon which the sides of the cabinet are supported.

Upon the upper end, and extending around 45 each side of the cabinet, is a strip of inwardly curved molding (h), above which is placed a strip of outwardly projecting fancy molding (i) which is in turn surmounted by the top of the cabinet, the latter projecting beyond said 50 molding.

Having described my design, I claim—
The design for a cabinet herein shown and 55 described.

In testimony whereof I affix my signature 60 in presence of two witnesses.

JOHN ELLIOT PEIRCE.
